Oscar Dingfeld

BY
Israel Benjamins. ATTORNEY

ATTORNEY

UNITED STATES PATENT OFFICE.

OSCAR DINGFELD, OF BROOKLYN, NEW YORK.

HEADGEAR FOR RELIEVING HEADACHES.

Application filed March 15, 1923. Serial No. 625,341.

To all whom it may concern:

Be it known that I, OSCAR DINGFELD, a citizen of the United States, residing at 249 Marion St., Brooklyn, in the county of 5 Kings and State of New York, have invented a new and useful Headgear for Relieving Headaches, of which the following is a specification.

My invention consists in the novel features 10 hereinafter more fully described, and the objects of it are:

First: to provide a means for applying pressure to certain points below the rear of the head, whereby the pressure of the blood 15 may be checked, thereby relieving the headache, which may be the result of or the accompaniment of the blood pressure.

Second: to have said means combined with a band or strap, which may be connected to 20 the head, thereby forming a headgear.

Third: to have said means adjustable for different persons; and fourth: to have my headgear for relieving headaches simple, durable and inexpensive.

I attain these objects by the device illustrated in the accompanying drawings or by 25 any mechanical equivalents or obvious modification of the same.

In the drawings Fig. 1 is an inside elevation on a small scale of one form of my headgear for relieving headaches when the latter is spread out into a plane.

Fig. 2 is an edge view in plan of the same headgear.

Fig. 3 is a sectional plan on a larger scale 25 of the middle part of a more perfect form of my headgear for relieving headaches.

Fig. 4 is a cross-section on the line 4—4 of Fig. 3.

Fig. 5 is a part plan of the left end of Fig. 3.

Figs. 6 and 7 are respectively a plan and an elevation of the sleeve 42—42^a, which is hereinafter more fully described.

Similar characters refer to similar parts throughout the several views.

11 designates an attachment member in the form of a band or strap, which terminates at one end thereof in the overlap 11^a, which has connected thereto the buckle 12, which is provided with the tongue or pin 13.

The other end of the band 11 terminates in the tip 14 and is provided with the holes or sockets 17 for said tongue or pin 13 to be adjustably interlocked there-

with, whereby the band or strap 11 may be 55 tightened on to the head of a person suffering from a headache, preferably with the buckle resting against the forehead of the person.

The part of the band 11, which is intermediate its ends, is provided with the openings 15, which are adapted to pass over the ears of any person; these openings 15 are shown in Fig. 1 as oblong, to allow for the difference in the size and position of the 60 ears in different persons, and they are encompassed by the rims 16, which may be of metal or any other suitable material.

At the middle of the band 11 I provide the laterally stationary pressure knobs 18 70 and the laterally adjustable pressure knobs 19, which may be adjustably secured in position in the slots 20.

One simple way of adjustably securing 75 said knobs 19 in the slots 20 is by having each knob terminate in a screw, which is shown in Fig. 2 as being in engagement with the wing nut 21, which is abutting at its inner end against the washer 22, which rests against the body of the band 11.

It is evident that, when the band 11 is buckled on to the head of any person, the knobs 18 and 19 will press against certain points in the back of the neck or below the rear of the head, which pressure may be adjusted by said wing nuts as above described.

The effect of that exterior pressure will be to check the blood pressure in the region of the head, whereby relief will be obtained from headaches.

To enable a person to recline with the above described band or strap on, and to permit adjustment of the pressure knobs from the outside of the band, without removing the same from the head, I provide the improved details of the preferred form of my headgear for relieving headaches, as illustrated in Figs. 3, 4, 5, 6 and 7, in which 95 31 designates the band or strap, of which the middle part only is shown, and 35 are the openings for the ears.

The rims 26, which are encompassing the openings 35, are made each in one piece with the plates 26^a, which may be thin and flexible or semiflexible and connected to the band or strap 31 in any suitable manner.

The laterally stationary pressure knob 28 and the laterally adjustable pressure knobs 29 terminate in the screws 28^a and

29^a respectively, which are in engagement with the sleeves 42—42^a, as shown in Figs. 3 and 4.

These sleeves consist each of the base 42^b and the neck 42^a, and each base has formed thereon the shoulders 42^b, as shown in Figs. 6 and 7.

Each of said sleeves 42—42^a has its base 42 inserted into a suitable opening in the 10 band 31 between the plates 26^a and with the shoulders 42^b in engagement with the edges of the outer one of said plates 26^a, whereby said sleeves are kept from being rotated; the caps 41 are then shrunk on or otherwise connected to the sleeves 42^a with the bases of 15 said caps 41 in contact with the plate 26^a, as shown in Figs. 3 and 4.

The slots 30 in the band 31 permit the outer two knobs 29 with their sleeves 42—42^a 20 to be adjustably secured in any of a large number of possible positions; these slots are larger in the body of the band 31 than in the plates 26^a, to make room for the bases 42 of the sleeves 42—42^a. Each of 25 said screws 28^a and 29^a has in its end a slot for a screw-driver, whereby it may be turned in the sleeve 42—42^a from the outside of the headgear, whereby the position of the pressure knobs 28 and 29 may be adjusted to fit the back of the necks or the 30 rear of the heads of different persons.

The outer sides of each of the caps 41 is smooth and flush with the end of the sleeve 42^a, thereby enabling a person, having the above described headgear on, to recline on a pillow comfortably without removing the headgear.

Many changes could be made in the details of my headgear for relieving headaches 40 without departing from the main scope of my invention; I do not, therefore, restrict myself to the details as shown in the drawings, but I intend to include also all me-

chanical equivalents and reasonably obvious modifications of the same within the scope 45 of my invention.

What I claim as my invention, and desire to secure by Letters Patent is:

1. In a headgear for relieving headaches the combination of a band, adapted to be 50 secured to the head of a person, a laterally stationary pressure knob, adapted to be placed opposite the middle part of the rear of the head when said band is in position, secured to said band, and a pair of laterally 55 adjustable pressure knobs on opposite sides of said stationary knob, adjustably connected to said band, said knobs being adapted to press on three points below the rear of the head, thereby relieving headaches. 60

2. In a headgear for relieving headaches the combination of a band adapted to be secured to the head of a person, one or more semiflexible plates secured to said band at the middle portion thereof, slots in said 65 band and said plates lengthwise thereof, sleeves adapted to be adjusted in position in said slots, said sleeves being secured against being rotated in said slots, and knobs, adapted to press on points below the 70 rear of the head of a person, adjustably connected to said sleeves.

3. In a headgear for relieving headaches the combination of a band adapted to be secured to the head of a person, sleeves 75 connected to said band, knobs, adapted to press on points below the rear of the head of a person, adjustably connected to said sleeves on the inner side of said band, and caps secured to the ends of the sleeves on 80 the outer side of the band, thereby retaining said sleeves in position, the outer sides of said caps being smooth and flush with the ends of said sleeves, thereby enabling a person to recline with the headgear on.

OSCAR DINGFELD.
